UNITED STATES PATENT OFFICE.

PETER PRESCOTT, OF BOONEVILLE, NEW YORK, ASSIGNOR TO HIMSELF AND
G. H. POST, OF SAME PLACE.

IMPROVEMENT IN LATHES FOR TURNING BROOM-HANDLES.

Specification forming part of Letters Patent No. 33,466, dated October 8, 1861.

To all whom it may concern:

Be it known that I, PETER PRESCOTT, of Booneville, in the county of Oneida and State of New York, have invented certain new and useful Improvements in Machinery for Turning Broom-Handles; and I do hereby declare that the following is a full, clear, and exact description thereof, reference being had to the accompanying drawings, making a part of this specification, in which—

Figure 1 is a longitudinal section through the improved machine in the vertical plane indicated by red line xx in Fig. 2. Fig. 2 is a top view of the machine complete. Fig. 3 is a back view of the plate which carries the grooving-cutter. Fig. 4 is a face or front view of the same. Fig. 5 is a front view of the cutter-head of Figs. 1 and 2.

Similar letters of reference indicate corresponding parts in the several figures.

To enable those skilled in the art to make and use my invention, I will proceed to describe its construction and operation.

A represents the table for containing and supporting the machinery which I am about to describe.

B B' B' are four rollers carrying the feed-wheels $a a' a'$, the former of which feed the work to the cutters, while the latter draw away the finished handles. Shafts B B' have pinion spur-wheels $b b' b'$ on their ends, the lower two of which wheels engage with a large spur-wheel C, as shown in Fig. 1 of the drawings, and as this wheel C is rotated in the direction indicated by arrows in Fig. 1 it gives rotary motion to the lower wheel b , and this wheel b rotates the upper wheel b' . The lower wheel b' rotates the upper wheel b' , and also the large wheel C. One of the lower shafts B' carries on one end a large spur-wheel B², which receives a rotary motion from the short tool-shaft D, through the medium of bevel-pinion c, large bevel-wheel c', and pinion spur-wheel d, and the four feed-wheels $a a' a'$ are thus rotated in the direction indicated by the arrows in Fig. 1, and they have a proper relative speed with that of the cutting device, as will be hereinafter fully explained. The upper feed-wheels $a a'$ should be allowed to have an upward yielding motion, so that they will accommodate

themselves to the varying thicknesses of poles which are passed between them.

The tool-shaft D is supported in bracket-bearings D' D', projecting out from and secured to one side of the table A, as shown in Fig. 2. On this shaft D are three belt-wheels $e e' e$, the middle one of which is fixed to the shaft D, and the side wheels $e e'$ are loose on this shaft. Thus when the belts which drive the shaft D are thrown off on either one of the side pulleys $e e'$ the shaft D will not be turned.

D² D³ are levers for shifting the belts which drive shaft D.

E is a strong beam, which extends longitudinally through the top of table A and which is in the middle of this table. On this beam or bed E the cutting apparatus is mounted.

F F are two stationary bearing-blocks supporting the hollow horizontal spindle G in their upper ends. This spindle G is arranged longitudinally between the two pairs of feed-wheels $a a' a'$ and in such a position with respect to these feed-rollers that the sticks passed between rollers $a a'$ will be directed into the hollow spindle G and by this spindle directed between the rollers $a a'$ at its opposite end.

G' is a belt-wheel which is keyed to the hollow spindle G, and over this wheel a belt passes, which communicates a rapid rotary motion to the spindle G from the main driving-shaft A'. The bearing-blocks in which spindle G turns do not allow this spindle to have any longitudinal or end play.

H is a flanged collar, which is put upon spindle G and allowed to have an end play only on this spindle. This collar H has an annular groove f in its periphery, into which groove plays a pin g, which is on the short arm of a bifurcated lever I, which is pivoted at g' to the table A. The long arm of this bifurcated lever I projects under the spindle G, and its end passes into a cam-groove h in the side of spur-wheel C, as shown in Fig. 1 of the drawings. The collar H will thus receive its end play on the spindle G from the cam-groove h in wheel C, through the medium of vibrating lever I. The flange H' on sliding collar H has two holes through it, which

receive pins *i i*, that project from expanding cutter-blocks *k k* through slotted holes which are made through the circular plate *G²*. The plate *G²* is secured on the end of the spindle *G*, (shown in Figs. 1 and 2,) and on the outside surface of this plate *G²* the knife-carrying blocks *k k* are pivoted, and as the collar *H* is moved back and forth on spindle *G* these knife-blocks *k k* are operated by the flange *H'* on this collar *H*, so as to give the desired taper to the stick, which is passed through the hollow spindle *G*. This tapering is effected by the movement of the collar *H* toward the plate *G²*, which causes the knives to gradually approach toward the center of the spindle as the stick passes through this spindle and is rounded.

Fig. 5 shows the knife-blocks *k k*, which are pivoted at *l l* to the plate *G²*. The knives *m m* have beveled cutting-edges, which cut away the wood and round the stick as it is fed between them by the rollers *a' a'*. The pins *i i*, which project from the back of the blocks through slotted holes through the plate *G²* and through holes in flange *H'*, diverge from the axis of the spindle, as shown in Fig. 1, so that when the collar *H* is moved toward the plate *G²* the knife-carrying blocks *k k* are moved away from the axis of the spindle, and when this collar *H* is moved from the plate *G²* the knife-blocks are made to approach the axis of spindle *G*.

The cutter-head *G³* (shown in Figs. 3 and 4 of the drawings) carries stationary knives *k k* on its outside surface, the cutting-edges of which knives are beveled outward, as described for the knives in Figs. 1, 2, and 5. On the back surface of the circular head *G³*, in Figs. 3 and 4, a knife-block *n* is pivoted, carrying a knife *p*. A pin *r* projects from the block *n*, which passes through a hole in the flange of collar *H*, and by means of a suitable cam, which is made to act upon the long arm of lever *I*, the knife *p* can be made to cut grooves in the broom-handle while the knives *k k* are rounding this handle. This single cutter *p* is intended merely to groove the han-

dles at proper points, and for plain handles it will not be used.

The operation of the machine above described is as follows: Motion is communicated to the main shaft *A'*, and from this shaft rotary motion is transmitted to the spindle *G* by a belt *s*, and also to the large spurred cam-wheel *C* and feed-roller shafts *B B' B'*, through belts, pulleys, and spur-wheels, as before described. The machine now being in motion, a stick of wood of the proper length is placed on the guide-table *N* and pushed endwise between the rollers *a' a'* and up to the rotating cutters *m m*, which round the stick as it is fed through the hollow spindle *G*. At the commencement of the operation of rounding the stick or handle the cutter-blocks *k k* are separated as far as they can be, and as the work progresses these cutters are made to gradually approach each other by the operation of collar *H* upon the pins *i i*, actuated by the forked lever *I*, one end of which works in a cam-shaped groove *h* in the large wheel *C*, while the other end plays in the annular groove *f* in collar *H*, all as before described. Then as the cutters *m m* are rounding the stick they are at the same time gradually reducing or tapering it, and as the smallest end of the rounded stick leaves the cutters this stick is received between the grooved rollers *a a*, which conduct the finished handle out of the spindle *G*. The cutter *P* on shaft *D* is used to round the small ends of the handles after they have passed through the spindle *G*.

Having thus described my invention, what I claim as new, and desire to secure by Letters Patent, is—

The arrangement of the pins *i*, perforated flange *H'*, and sliding collar *H* with the slotted circular plate *G²*, pivoted knife-blocks *k k*, and pivoted cutter carrier *n*, as herein shown and described.

PETER PRESCOTT.
